UNITED STATES PATENT OFFICE.

RUFUS H. GOULD, OF WORCESTER, MASSACHUSETTS.

LOCKING DEVICE FOR CLOTHES REELS.

Application filed March 21, 1927. Serial No. 177,009.

This invention relates to clothes reels of the porch type which are rotatably mounted on the laterally projecting arm of a supporting standard. It is desirable to be able to hold such a reel from rotation during the placing of articles thereon, and also to be able to prevent rotation of the reel when exposed to heavy winds.

It is the object of my invention to provide an improved locking device for such reels, effective to engage any one of the arms of the reel and to thereby prevent the rotation of said reel. A further object is to provide a locking device which may be easily and cheaply constructed and which may be readily applied to reels already in use, as well as to reels in the process of manufacture.

A preferred form of the invention is shown in the drawings in which

Fig. 1 is a side elevation of a reel having my improved locking device applied thereto; and

Fig. 2 is a plan view of the locking device.

Referring to the drawings, I have shown a clothes reel of the porch type comprising a plurality of arms 10 pivoted at 11 to a member 12 rotatably secured on a supporting structure.

This supporting structure comprises an upright standard 13 mounted in bearing brackets 14 and 15 firmly secured to the wall W of a house or to some other suitable frame work. A supporting arm 16 projects laterally from the upper end of the upright standard 14, and the member 12 is pivoted to a depending portion 17 of the arm 16.

Links 18 connect the arms 10 to a collar 19 slideable on the depending portion 17. The links 18 and collar 19 limit the opening movement of the arms 10 in the usual manner.

An arm 20 is preferably secured to the lower end of the upright standard 13 and may be provided with a handle 21 pivoted to said arm 20 and adapted to be placed between forks 22 and 23 by which the angular position of the supporting arm 16 may be determined.

The parts thus far described are of the usual construction and in themselves form no part of my present invention, which relates more particularly to my improved locking device for at times preventing rotation of the arms 10.

My improved locking device comprises a U-shaped locking member 24 having side

portions 25 and a connecting portion 26. The locking member 24 is pivoted to a block 27 having clamping arms 28 projecting therefrom and having a clamping bolt 29 extending through the openings in said arms. A bolt 30 forms the pivotal connection between the side portions 25 of the locking member 24 and the block 27.

The locking member 24 is preferably formed of wood, so that it will not stain or discolor the arms 10 when engaged thereby, or the articles of clothing mounted on the reel, should they happen to swing against the locking device.

In using the device, the clamping arms 28 are first secured to the upright standard 13, and the U-shaped locking member is then pivotally connected to the block 27 by inserting the bolt 30. The side portions 25 of the locking member 24 extend on both sides of the supporting arm 16. When the device is in locking position, the connecting portion 26 engages the top surface of the arm 16. When thus positioned, the locking member 24 extends diagonally across the corner of the reel supporting means, and is adapted to enclose and position one of the reel arms 10.

The reel may be released by merely swinging the locking device to the dotted line position shown in Fig. 1, in which position the reel arms are free to move. The device is thus exceedingly simple but very effective for the purpose intended, and may be used without danger of staining or discoloring the clothing on the reel. When not in use, it is out of the way and does not interfere in the slightest with the rotation of the reel.

Having thus described my invention and the advantages thereof, I do not wish to be limited to the details herein disclosed otherwise than as set forth in the claims, but what I claim is:—

1. The combination with a rotatable clothes reel having a plurality of spaced radially disposed arms and supporting means for said reel comprising an upright standard having an arm projecting laterally therefrom to which the reel is connected, of a locking device for said reel comprising a U-shaped member pivoted on said upright standard and having its transverse portion adapted to engage said laterally projecting arm when in locking position, with the legs of said U-shaped member located one at each side of a selected radial arm.

2. The combination with a rotatable
